UNITED STATES PATENT OFFICE.

GEORGE APSLEY, OF LOCK HAVEN, PENNSYLVANIA.

SEAMLESS SHOE.

SPECIFICATION forming part of Letters Patent No. 374,571, dated December 13, 1887.

Application filed September 3, 1887. Serial No. 218,714. (No model.)

To all whom it may concern:

Be it known that I, GEORGE APSLEY, a citizen of the United States, residing at Lock Haven, in the county of Clinton and State of Pennsylvania, have invented certain new and useful Improvements in Seamless Shoes; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 The special object of the invention is to make a shoe-upper in one piece, so as to avoid the ripping of seams and the hurting of the feet.

Figure 1 is a plan view of the pattern after it has been crimped and prepared for use; 20 Fig. 2, a perspective view broken away to show the three plies through which the eyelets pass.

In the drawings, B forms the integral upper, having the vamp b and quarter b' b² integral, 25 the quarter part b' being folded at b³ inwardly to form an integral lining. The vamp b has a slot, b⁴, and the part b' of the quarter a slot, b⁵, and loose end b⁶. By conjoining the slots b⁴ b⁵, the placing of said part b' around the outside of

vamp b, and drawing the loose end b⁶ on the 30 inside of vamp b, the vamp and part b' of the quarter are securely locked together. The tongue C is now placed under the fold b⁷ of the upper and the three plies eyeleted together at c c, thus holding fast the sides of upper and 35 the tongue. Thus it will be seen that two eyelets are always necessary in my seamless shoe.

I may put on the shoe a gaiter top, or a buttoned, a congress, or a high hook-lace one, and may cut out the lining below the two eyelets. 40

Having thus described all that is necessary to a full understanding of my invention, what I claim as new, and desire to protect by Letters Patent, is—

1. A shoe-upper formed of the vamp b and 45 quarter b' b² in one piece, the part b' of the quarter being folded on the vamp b and locked by the open slots b⁴ b⁵, as shown and described.

2. In a seamless shoe-upper, the vamp b, part b' of the quarter, and tongue C, combined 50 with and secured together by two eyelets, c c, as shown and described.

In testimony whereof I affix my signature in presence of two witnesses.

GEORGE APSLEY.
